UNITED STATES PATENT OFFICE.

FREDERICK J. HARDMAN, OF DAYTON, OHIO, ASSIGNOR TO GENERAL MOTORS CORPORATION, A CORPORATION OF DELAWARE.

ELECTRICAL STARTING APPARATUS.

Application filed July 15, 1924. Serial No. 726,211.

To all whom it may concern:

Be it known that I, FREDERICK J. HARDMAN, a citizen of the United States of America, residing at Dayton, county of Montgomery, and State of Ohio, have invented certain new and useful Improvements in Electrical Starting Apparatus, of which the following is a full, clear, and exact description.

10 This invention relates to a type of engine starting apparatus which includes an electric motor and mechanical connections between the motor and engine including an engine gear, a normally demeshed pinion and means whereby, after the pinion has been meshed with the engine gear, the pinion may be moved by motor operation into full driving engagement with the engine gear, and whereby the pinion may be automatically demeshed from the engine gear when the engine starts.

20 The present invention provides improved means for manually shifting the pinion into engagement with the engine gear and for closing the motor switch, and for automatically changing the leverage of the manually operated shifting means with respect to the pinion, so that the pinion will be demeshed regardless of continued manipulation of the shifting means.

30 The invention provides a pinion shifting lever, a movable rod connected with the lever by connections permitting a change of leverage of the rod with respect to the lever, and means for causing the rod to move endwise to move the lever and to shift the pinion into engagement with the engine gear, and for tending to produce sidewise movement of the rod to reduce the ability of the 40 rod to maintain the shifting lever out of normal position. The connections between the rod and lever are such as to prevent the sidewise movement of the rod until after the pinion and gear are engaged and the 45 motor has been started.

These objects and other objects of the invention will be apparent from the following description of a preferred form thereof, reference being made to the accompanying 50 drawings.

In the drawings:

Fig. 1 is a fragmentary side elevation, partly in longitudinal section, of a form of starting apparatus embodying the present 55 invention;

Fig. 2 is a view taken substantially on the line 2—2 of Fig. 1;

Fig. 3 is a view similar to Fig. 1, showing the apparatus in position for engine cranking; and

Fig. 4 is a fragmentary sectional view on the line 4—4 of Fig. 1.

In the drawings, 20 designates an electric motor which drives a shaft 21, provided with spiral splines 22, a stop collar 23 and a stop shoulder 24,—the latter being integral with the shaft or provided by means of a separate tubular member surrounding the shaft. The motor 20 includes a field frame 25 attached to a gear housing 26, providing one of the end frames of the motor and supporting a bearing 27 and one end of the shaft 21. The left-hand end of shaft 21 (not shown) is supported by the field frame 25 in a well-known manner. Thrust washers 28 are located between the stop collar 23 and a machined surface 29 provided by the housing 26.

35 A pinion 30 threadedly engages the spiral splines 22 and has a hub 31 provided with flanges 32 and 33 including a groove 34. The groove 34 is engaged by a shifting lever having bifurcations 40 and 41 connected by yoke 42 and pivoted upon a rod 43, supported by brackets 44 and 45 which are formed integral with the housing 26. A set screw 46 maintains the rod 43 in position as shown in Fig. 2. A spring 47 encircles a spacing sleeve 48 surrounding the rod 43, and said spring bears at one end 49 upon the housing 26 and at the other end 50 against the yoke 42.

40 The mechanism for shifting the lever 40, 41 comprises a pedal 51 attached to a rod 52 connected at its lower end with a lever 53 by a pin 54. The lever 53 is attached to a hub 55 which journals the lever 53 upon the rod 43. The pin 54 is provided with a head 56 limiting endwise movement of the pin 54 in one direction, said pin being secured against endwise movement in the opposite direction by a washer 57 and a cotter pin 58. The head 56 is provided with a hole for receiving a rod 59, having at its upper end screw threads for engaging nuts 60 and at its lower end a head 61 provided with a flange 62 and a ball 63 received by a socket 64 which is attached by a set screw 65 to a rod 66 (see Fig. 4). A spring 67 encircles the rod 69 and is held normally in 66

initial state of compression between the flange 62 of the rod 59 and the head 56 of pin 54.

The rod 66 is endwise movable thru a block 68 having a trunnion 69 which pivotally supports the block 68 upon a switch case 70 or other suitable bracket. The rod 66 carries a collar 71 which may be adjusted along the rod 66 and secured thereto by a screw 72. Rod 66 carries at one end a fork 73 extending on both sides of the shifting lever arm 40, which is provided with an irregular opening 74 for receiving a roller 75 journaled on a pin 76 which passes through the branches of the fork 73 and through the opening 74. Endwise movement of the pin 76 is limited by its head and by a cotter pin 78. The opening 74 includes a notch 79 for a purpose to be described.

20 The switch case 70 supports a switch actuating plunger 80 normally maintained by a spring 81 in position shown in Fig. 1, the plunger 80 being arranged in the path of movement of a screw 82. The screw 82 is 25 endwise movable through a hole provided by the lever 53 and is secured in the required position of adjustment by nuts 83 and 84. The switch case 70 is secured by a screw 30 85 to the motor frame 25 and carries a switch terminal 86 adapted to be connected with a source of current. The plunger 80 carries a movable contact (not shown) which cooperates in a well-known manner with stationary contacts,—one being connected with the terminal 86 and the other with the field windings of the motor.

35 The pedal 51 and parts connected therewith, are maintained normally in the position shown in Fig. 1, by a spring 90 40 encircling the rod 52 and located between the pedal 51 and the cup member 91, supported by the floor 92 of the automobile, and provided with an opening through which the rod 52 extends.

45 The operation of the invention is as follows:

To start the engine the pedal 51 is depressed, thereby pushing the lever 53 downwardly, which transmits the motion through the spring 67 to the collar 64. This motion tends to move the rod 66 endwise through the block 68 and to rotate the rod 66 in a clockwise direction. Endwise movement of the rod 66 to the left of the drawings, causes the lever 40 to be moved in a counter-clockwise direction, and to engage the flange 33 and shift the pinion 30 into mesh with the engine gear 100.

50 As long as the pinion 30 is being moved to the right by reason of pressure exerted by the pedal 51, the roller 75 will be retained within the notch 79 of the opening 74. Therefore, the rod 66 will not turn in a clockwise direction, although there is a tendency for it to turn in this direction

due to the direction of the force applied by the spring 67.

In case the pinion 30 is introduced into mesh with the gear 100, by operation of the pedal, without the pinion 30 abutting the teeth of the gear 100, the motor switch plunger 80 will be engaged by the screw 82 after the gears 30 and 100 have been meshed. After closing the motor switch by pedal operation, the motor will operate to move the pinion 30 against the stop collar 23 and into full driving engagement with the gear 100. When the motor switch is closed by the engagement of screw 82 with plunger 80, as shown in Fig. 3, the stop collar 71 75 engages the block 68, thereby limiting the movement of the rod 66 to the left by virtue of pedal operation. Consequently, movement of the roller 75 toward the left will be arrested. However, the operation of the motor to thread the pinion 30 toward the right after having been engaged with the gear 100, causes the flange 32 connected with pinion 30 to engage the lever 40 and finally move it into the position shown in full lines in Fig. 3. Motion of the lever 40 relative to the roller 75 is produced, thereby moving the notch 79 away from the roller 75. When this occurs, the rod 66 will move into the position shown in Fig. 3, due to the action of spring 67.

The effect of the pressure by roller 75 upon the lever 40 is reversed by the movement of roller 75 from the position shown in Fig. 1 to the position shown in Fig. 3. In Fig. 1, the action of the roller is to move the lever 40 counter-clockwise, but in Fig. 3, the action of roller 75 is to move the lever 40 clockwise. Therefore, when the engine becomes self-operative and the gear 100 tends to overrun the gear 30, the gear 30 will be automatically disengaged from gear 100 due to the spiral-spline connection between gear 30 and the shaft 21. Gear 30 is free to move toward the left into the normal position shown in Fig. 1, although the pedal 51 may not yet be released, because the connections between the pedal 51 and the lever 40 have been modified. The leverage of pressure exerted by roller 75 upon the lever 40, having been reversed, as previously explained, the lever 40 is free to turn into its normal position indicated by 110 40^a in Fig. 3. The demeshing of the gear 30 from the gear 100 is assisted, therefore, by the action of the roller 75 as well as by the action of spring 47.

The release of pedal 51 permits the spring 90 to return the rod 52 and pedal to normal position. As the lever 53 moves upwardly, the head 56 of pin 54 will engage the adjacent nut 60, thereby causing the rod 59 to move upwardly and the rod 66 to return to the position shown in Fig. 1. During the upward movement of roller 75, it will bear

against the surface 74^a at one side of the opening 74. The pressure between the roller 75 and the surface 74^a is yieldingly maintained by the action of the spring 47. As the roller 75 approaches the notch 79, the lever 40 will yield slightly in a counter-clockwise direction; and, finally, the roller 75 will be received by the notch 79 as the lever 40 finally returns to normal position as shown in Fig. 1. Release of the pedal 51 permits the spring 81 to return the plunger 80 to normal position and thus open the motor switch.

In case the teeth of the gear 30 fail to register with the tooth spaces of gear 100 so that registration is prevented by abutment of the teeth of gears 30 and 100, motion of the lever 40 and rod 66 will be arrested. Continued pressure upon the pedal 51 will cause the screw 82 to engage the plunger 80 and close the motor switch. The motor will rotate the shaft 22 slightly to register the gear 30 with tooth spaces of the gear 100. The spring 67, which has been further compressed by the operation of pedal 51 to close the motor switch, will be released to move or "jump" the pinion 30 into engagement with the gear 100. After this occurs, the operation of the motor will move the pinion 30 into full driving engagement against the stop 23, and the connections between the pedal 51 and the lever 40 will be modified as described heretofore.

In case the engine should fail to start after the gears 30 and 100 have been engaged, the gear 30 would remain in engagement with the gear 100. However, the pedal 51 may be released and the motor switch will open so that operation of the motor will be discontinued.

It is apparent from the foregoing description that if the connections between the pedal 51 and lever 40 were not modified, the demeshing of the pinion 30 from the gear 100 would be hindered by continued pressure by the operator, upon pedal 51. In the present invention these connections are so modified, that instead of being a hindrance, continued pressure upon the pedal 51 after the engine starts is slightly beneficial to the automatic disengagement of the pinion 30 from the gear 100.

While the form of embodiment of the invention as herein disclosed, constitutes a preferred form, it is to be understood that other forms might be adopted, all coming within the scope of the claims which follow.

What is claimed is as follows:—

1. Engine starting apparatus comprising, in combination, a gear connected with an engine to be started; and electric motor; driving connections between the motor and engine gear including a pinion driven by the motor and movable into engagement with the engine gear, said connections in-

cluding means whereby the pinion will be moved by motor operation into full driving engagement with the engine gear after having been meshed therewith, and whereby the pinion may be automatically disconnected from the engine gear when the engine becomes self-operative; a motor switch; and means for moving the pinion into contact with the engine gear and for closing said switch, said means including a pinion shifting lever, a movable rod, connections between the rod and lever permitting the leverage of the rod with respect to the lever to be changed, and means for causing the rod to move endwise to move the lever and to shift the pinion into engagement with the engine gear and for tending to produce sidewise movement of the rod to reduce the leverage of the rod with respect to the lever, said connections normally preventing said sidewise movement but released by the operation of the motor in moving the pinion into full engagement with the engine gear.

2. Engine starting apparatus comprising, in combination, a gear connected with an engine to be started; an electric motor; driving connections between the motor and engine gear including a pinion driven by the motor and movable into engagement with the engine gear, said connections including means whereby the pinion will be moved by motor operation into full driving engagement with the engine gear after having been meshed therewith, and whereby the pinion may be automatically disconnected from the engine gear when the engine becomes self-operative; a motor switch; and means for moving the pinion into contact with the engine gear and for closing said switch, said means including a pinion shifting lever, a pivoted and endwise slidable rod, a part carried by the free end of the rod and engaged by a notched portion of the lever, means for causing the rod to move endwise to move the lever and to shift the pinion into engagement with the engine gear and for tending to produce sidewise pivotal movement of the rod to reduce the leverage of the rod with respect to the lever, and means for limiting endwise movement of the rod to that required for partial engagement of pinion and gear, said notch being constructed and arranged so that the part is retained within the notch while pressure is being transmitted from the rod to the lever at the notch, the part being freed from the notch to permit the rod to move sidewise by the operation of the motor in moving the pinion into full engagement with the engine gear.

3. Engine starting apparatus comprising, in combination, a gear connected with an engine to be started; an electric motor; driving connections between the motor and engine gear including a pinion driven by the

motor and movable into engagement with the engine gear, said connections including means whereby the pinion will be moved by motor operation into full driving engagement with the engine gear after having been meshed therewith, and whereby the pinion may be automatically disconnected from the engine gear when the engine becomes self-operative; a motor switch; and 10 means for moving the pinion into contact with the engine gear and for closing said switch, said means including a pinion shifting lever, a rod slidably pivoted upon a stationery part, a roller carried by the free 15 end of the rod and engaged by a notched portion of the shifting lever, a pedal operated lever pivoted concentrically of the shifting lever, a yielding connection between the pedal lever and rod for causing the rod to move endwise to move the shifting lever 20 and to shift the pinion into engagement with the gear and to tend to move the rod sidewise to reduce the leverage of the rod with respect to the lever, and means for limiting the endwise movement of the rod 25 to that required for partial engagement of pinion and gear, said notch being constructed and arranged so that the roller is retained within the notch while pressure is being transmitted from the rod to the lever 30 at the notch, the roller being freed from the notch to permit the rod to move sidewise by the operation of the motor in moving the pinion into full engagement with the engine gear. 35

In testimony whereof I hereto affix my signature.

FREDERICK J. HARDMAN.
